STIFFENER AND ALIGNER FOR HOLLOW METAL DOORS AND CASEMENT WINDOWS

Filed Oct. 12, 1928

Clarence Walker

His Attorney

UNITED STATES PATENT OFFICE

EDWARD H. ELLISON, OF JAMESTOWN, NEW YORK, ASSIGNOR TO ELLISON BRONZE COMPANY, INC., OF FALCONER, NEW YORK, A CORPORATION OF NEW YORK

STIFFENER AND ALIGNER FOR HOLLOW METAL DOORS AND CASEMENT WINDOWS

Application filed October 12, 1928. Serial No. 312,092.

This invention relates to an improvement in a stiffener and aligner for hollow metal doors and casement windows.

Prior to this invention much difficulty has been encountered in building hollow metal doors by reason of the fact that the various elements which go to make up each door have, during work performed upon them, become slightly bent or twisted and as a result the assembled door is of more or less misaligned proportions. While it is true that in the producing of a hollow steel door it is possible to so accurately cut and assemble the parts as to produce a perfectly aligned door, such procedure requires much more time than is commercially practical and is therefore seldom resorted to. Oftentimes hollow metal doors are made up from sheet bronze or brass. When producing a door from either of these metals it is necessary to rivet the various elements together because of the fact that these metals are subject to warping or twisting when heat is applied. It is possible to produce doors of either of these materials of perfect proportions but prior to this invention no method of twisting doors of this type has been available which would not tend to loosen the rivets. Obviously, any metal door can be twisted under pressure to align it with itself or an adjacent door but such procedure results in loosening the rivets which hold the elements together. Applicant's device, on the other hand, when used in conjunction with doors made of either bronze or brass is capable of slightly bending or twisting the door into the desired alignment without loosening the rivets thereof.

It often happens that a hollow metal door while perfectly aligned with itself will not hang properly within a door frame due to inaccuracies in assembling said frame. This is particularly true of a double door frame in which the stop for the doors is along the upper edge of the frame only. Under such circumstances a pair of doors may each be perfectly aligned with itself and each other and yet when hung from opposite sides of the door frame, the free edges thereof will be out of alignment. Through the provision

of a stiffener and aligner in each door it is possible to slightly twist the top or bottom of either of the doors to bring them into perfect alignment with each other.

The assembling and mounting of casement windows is also subject to much the same difficulties as obtain with respect to hollow metal doors and it is contemplated to provide applicant's device in such forms as may be applicable to align casement windows with themselves and within their frames.

In the following specification applicant discloses a device for use within and in conjunction with a hollow metal door, access to which is had from the exterior of said door whereby to stiffen and align the door from almost any warped position it may have assumed during assembling.

The principal object of this invention is the provision of a hollow metal door having an adjustable stiffener and aligner located therein which is adaptable to adjustment from the exterior of the door.

Another object of this invention is the provision of a stiffener within the stiles of a hollow metal door having arms, one of which is accessible of adjustment from the exterior of the door.

Other and further objects of this invention will appear from a consideration of the following specification taken in connection with the accompanying drawings, and in which;

Fig. 1 is a front elevation of a hollow metal door showing one modification of a door stiffener and aligner in dotted lines;

Fig. 2 is a side elevation of the stiffener and aligner indicated in Fig. 1;

Fig. 3 is a plan view of Fig. 2;

Fig. 4 is a greatly enlarged vertical sectional view taken on the line 4—4 of Fig. 1 and illustrates the means by which the upper and horizontal arm of the stiffener is made use of to align the door;

Fig. 5 is an enlarged vertical sectional view taken on the line 5—5 of Fig. 1 and illustrates the manner of pivotally securing the upper vertical end of the stiffener to the door;

Fig. 6 is a plan view of a modification of this invention illustrating the use of a hol-

low metal upright in place of the solid member shown in the previous figures of the drawing; and

Fig. 7 is a vertical sectional view of the modification shown in Fig. 6, illustrating the manner of securing the horizontal arms to the hollow upright member.

Referring to the drawing, this invention is applicable for use within a hollow metal door indicated by the reference numeral 10. The door 10 is formed with a hollow stile 11 and rail 12, the upright 14 of the stiffener 13 being mounted within said stile. Secured to the top and bottom of the upright 14 and extending at right angles thereto within the rails 12 are arms 15 and 16. The upper arm 15 is secured adjacent its end 17 to the upper edge of the upright 14 in any suitable manner as by welding. In the end 17 of the arm 15 an opening 18 is drilled which coincides with a threaded opening 19 provided in the upright 14. The purpose of these openings will later be brought out in connection with other details of construction. The free end 20 of the arm 15 has horizontally drilled and tapped openings 21 and 22 extending therethrough. Attention is called to the fact that the end 20 is of a considerably lesser width than the end 17 the purpose of which is to provide clearance for movement of the rail 12 horizontally of the arm 15 to accomplish the aligning of said door. Although the arms 15 and 16 are shown as being of a length slightly greater than one-half the width of the door, it is contemplated to use longer or shorter arms as required to align various types of doors.

The arm 16, secured in any suitable manner as by welding to the bottom of the upright 14, is of a length equal to that of the arm 15. This arm is preferably of a uniform width throughout its length and is provided with a number of spaced vertical openings 23. It is contemplated, however, to construct the arm 16 similarly to the arm 15 when the warping of a heavy door is to be overcome.

Within the upper rail 12 of the door 10, and extending the full length thereof, is mounted the usual supporting channel member 24, the side walls 25 of which abut the inner faces of the rail. The width of the arms 15 and 16 is such that they will rest within the space formed by the channel 24. Mounted upon the upper face and adjacent the end 17 of the arm 15 is a small channular member 27, the side walls 28 of which closely engage the side walls 25 of the channel 24. An opening 30 in the base wall 29 of the channel 27 is provided, said opening being directly in line with the openings 18 and 19 in the arm 15 and upright 14. A stud 32 is passed through the openings 30 and 19 in the upright. It is to be noted that inasmuch as the channel 27 is secured against any horizontal movement by its engagement with

the channel 24, when the stud 32 ties the channel 27 to the arm 15 and upright 14, said upright and arm are provided with a pivotal point about which they may move with relation to said channel when the end 20 of the arm is moved from one side to the other.

The arm 16 is rigidly secured to the base of the stile channel 34 by means of studs 35 which are passed through openings 36 in said channel and brought into threaded engagement with the openings 23 of the arm. Inasmuch as the arm 16 and the lower end of the upright 14 are rigidly secured to the door rail, they act to resist any twisting of the upright by the upper arm 15.

When it is contemplated to assemble a hollow metal door embodying this invention, the following steps are to be observed: The stiffener 13, having been assembled into the unit shown in Fig. 2 of the drawing, is inserted within a door.

The channel member 27 is secured in place upon the arm 15 by the stud 32 and the lower arm 16 is secured to the channel 34 through the use of the studs 35. When this has been done the stiffener 13 is permanently mounted within the door and the door may be finally assembled. Through possible negligence in constructing the various elements or through warping of the metal, the assembled product may be somewhat misaligned and in order to bring about a perfect alignment screws 39 and 40 are provided. These screws are adapted to engage the outer end 20 of the arm 15 through the openings 21 and 22, said screws being engaged with said arm from opposite sides of the door rail 12.

Should the upper portion of the door be warped to occupy the position shown in dotted line in Fig. 4, the outer end of the arm 15 will be found to be considerably off center and, in order to straighten the door by means of the stiffener, the screw 39 is turned to draw the remote edge of the door toward the arm 15 until the misaligned portion of said door is in align with the balance of the structure. The screw 40 may now be turned as far as possible and when this has been done the upper portion of the door will be rigidly held in engagement with the arm 15.

It is to be noted that the upright 14 and arms 15 and 16 are of a sufficient strength to remain absolutely rigid when a door is being aligned. It is to be further noted that the rigidity present in the stiffener and aligner is of itself equal to the non-twisting safety factor required of a door and consequently any door, whether it be properly constructed or not, when once equipped with this device will have the required stiffness and strength to resist twisting during its entire life. The pivotal means provided through the use of the channel member 27 and the stud 32 is for the purpose of permitting the edge of the door remote from this pivotal point move-

ment with relation to the stiffener and aligner.

While it is contemplated to make use of a stiffener and aligner having a solid metal upright, it is obvious that under certain circumstances, particularly when a light weight door is required, the upright 13 would materially add to the weight of the door. Under such circumstances the modification shown in Figs. 6 and 7, providing a hollow metal upright 41, is preferred. The vertical walls of the hollow upright 41 are welded or otherwise suitably secured together. The ends of the upright 41 are welded or otherwise rigidly secured to the inner faces of the arms 15 and 16. It is obvious that a hollow upright 41 has not the resistance against twisting that the solid upright 14 has but since an upright of this kind is to be used in connection with small or light weight doors, its rigidity will more than equal the safety factor required for doors of this type.

While only two modifications of this invention have been shown and described, applicant does not intend to be limited thereto since it is obvious that other modifications and adaptations may be made without departing from the spirit and scope of this invention as set forth in the following claims.

Having thus set forth my invention what I claim is new and for which I desire protection by Letters Patent is:

1. A stiffener and aligner for a hollow metal structure comprising an upright body member, arms rigidly secured to and extending at right angles to said upright member, means supporting one end of said upright and adjacent end of one of said arms on said structure and adjustable means on one of said arms adapted to act upon and move the misaligned portion of said structure into alignment.

2. A stiffener and aligner for a hollow metal structure comprising an upright body member having upper and lower arms rigidly secured to said upright, means supporting the upper end of said upright, said means being in fixed engagement with said structure and adjustable means on one of said arms adapted to act upon and move the misaligned portion of said structure into alignment.

3. A stiffener and aligner for a hollow metal structure comprising an upright body member, horizontally extending arms rigidly secured to the top and bottom of said upright member, a channel member secured to said structure, means engaging said upright and one of said arms with said channel and adjusting screws engaging the free end of one of said arms with said structure whereby when either of said screws is actuated, the adjacent portion of said structure will be moved into aligned position.

4. A stiffener and aligner for hollow metal doors comprising an upright body member, horizontally projecting arms rigidly fixed to

the top and bottom of said upright member, a channel member secured to said door, a stud securing said upright and the upper of said arms to said channel, said upper arm being tapered toward its free end and adjustable means adapted to engage said free end and said door whereby when said means is actuated the upper portion of said door will be brought into alignment with either the lower portion thereof or an adjacently hung door.

5. A stiffener and aligner for hollow metal doors comprising an upright body member having horizontally projecting arms rigidly fixed to the top and bottom thereof, means mounting one end of said upright and the adjacent arm with relation to said door, the upper of said arms being tapered toward its free end and screws adapted to engage said free end and said door whereby said door adjacent said upper arm may be moved into alignment with the lower portion thereof or an adjacently hung door by actuation of said screws.

6. A stiffener and aligner for hollow metal doors comprising an upright body member having horizontally projecting arms rigidly fixed to the top and bottom thereof, a channel member in fixed engagement with said door, a stud securing one end of said upright and the adjacent arm with relation to said door, the upper of said arms being tapered toward its free end and screws adapted to engage said free end and said door whereby said door adjacent said upper arm may be moved into alignment with the lower portion thereof or an adjacently hung door by actuation of said screws.

In testimony whereof I have affixed my signature.
